RAILWAY TRACK SIGNAL

Filed Sept. 17, 1930

INVENTOR.
by RONALD M. WILSON.
Donald Reed.

his ATTORNEY.

UNITED STATES PATENT OFFICE

RONALD M. WILSON, OF WEST CHESTER, PENNSYLVANIA, ASSIGNOR TO THE HUFFMAN MANUFACTURING COMPANY, OF DAYTON, OHIO, A CORPORATION OF OHIO

RAILWAY TRACK SIGNAL

Application filed September 17, 1930. Serial No. 482,458.

This invention relates to a railway track signal and more particularly to that type of signal adapted to be mounted on a rail of a siding to indicate to the crew of a switch engine that a car on the siding is not to be moved, as for example, when a tank car is connected with a discharge conduit for the purpose of discharging its contents to a storage reservoir.

One object of the invention is to provide a signal of this kind which may be easily attached to the rail and will be firmly supported thereon with the signal in an elevated position.

A further object of the invention is to provide such a signal which when placed in position on the rail will be self-supporting and will not require the use of clamps or other fastening devices to secure it to the rail.

A further object of the invention is to provide such a signal with a supporting structure having rail engaging parts of such a character and so arranged that they will be retained in supporting engagement with the rail by gravity.

Other objects of the invention will appear as the device is described in detail.

In the accompanying drawings Fig. 1 is a side elevation of a signal embodying my invention; Fig. 2 is a perspective view of the lower portion of the supporting structure of such a signal; and Fig. 3 is a side elevation of the lower portion of a slightly modified form of the supporting structure; Fig. 4 is a view of a modification.

The signal as a whole comprises a suitable sign or indicating member, which constitutes the signal proper, and which is carried by a supporting structure having at its lower end two parts adapted to be positioned on opposite sides of the rail on which the device is to be mounted and to have supporting engagement therewith. This supporting structure has a part extending laterally beyond one side of the rail and the lower end parts thereof are so arranged that, when the structure is properly positioned on the rail, the weight of said laterally extending part will hold one of said lower end parts in engagement with the base flange of the rail on that side of the rail adjacent to said laterally extending part,

and will hold the other lower end part in engagement with the underside of the rail head on the other side of the rail, thus causing the signal as a whole to be supported by gravity in its operative position on the rail without the use of a clamp or retaining device of any kind.

The supporting structure may take various forms and in that particular embodiment of the invention shown in Figs. 1 and 2 this supporting structure is in the nature of a standard 5 having secured to its upper end the signal proper, which is shown at 6 as a stop sign. The lower end of the standard 5 has a part adapted to engage beneath the head of the rail 18 on one side of the rail and the standard extends across the rail in an upwardly inclined position so that when the structure is properly supported on the rail the upper end thereof is laterally offset beyond that side of the rail opposite the side which is engaged by the lower part of the standard. In the present instance, the lower end of the standard is bent downwardly and inwardly, as shown at 7, so that it will hook under the rail head and has rigidly secured thereto a transverse bar 8 adapted to seat in the angle between the lower side of the head and the vertical web of the rail. Mounted on the standard at a point spaced from the lower end thereof is a member 80 adapted to extend downwardly on that side of the rail opposite the lower end of the standard and to have supporting engagement with the base flange of the rail. This member is shown in the form of an arm 9 having rigidly secured to its lower end a transverse bar 10 arranged to seat in the angle between the base flange and the web of the rail. When the supporting structure is positioned on the rail with the rail engaging parts in their proper positions the weight of the offset portion of the standard will hold the parts in those positions and the engagement of the parts with the rail will hold the standard in its inclined position with the signal in an elevated position. The rail engaging bars 8 and 10 are of sufficient length to hold the structure against tilting movement in the direction of the length of the rail. While I have here

100

shown both the standard and the arm as provided with elongated parts or bars to hold the structure against tilting it will be obvious that this result may be attained by an elongated rail engaging part on one of said members only. The second member or arm 9 may be connected with the standard in any suitable manner but, in the form here shown, the arm is pivotally mounted on the standard, 10 preferably by pivotally connecting the same to a clip 11 which is rigidly secured to the standard, by welding or otherwise. The upper end of the arm 9 may be extended above the axis of the arm and bent outwardly away 15 from the standard, as shown at 12, to form a handle by means of which the arm may be manipulated, for the purpose of placing the supporting structure on and removing the same from the rail. If desired, the arm may be connected with the standard by a spring 20 13 which, when the device is not in use, will hold the arm in contact with the lower end of the standard and prevent the same from flopping about when the signal is carried from one position to another, but this spring has no function in so far as the connecting of the supporting structure with the rail is concerned. It is immaterial which of the members engages the base flange and which 25 engages the rail head, and it will be apparent that the same result may be secured by reversing the arrangement shown in Figs. 1 and 2, and causing the standard to engage the base flange and the arm to hook under the 30 rail head.

In Fig. 3 I have illustrated a modified form 35 of the supporting structure in which the two members are rigidly connected one to the other. In the particular arrangement there shown the standard 14 has its lower end arranged to engage the base flange of the rail on that side of the rail adjacent to the standard and the upper portion of the standard extends laterally in a direction away from 40 the rail. The arm 15 is rigidly secured to the standard, by welding or otherwise, extends across the rail and has its lower end adapted to engage the underside of the rail head on that side of the rail opposite the 45 standard. If the rail head is of greater width than the space between the rail engaging parts of the two members the structure may be attached to the rail by moving the same in a reverse direction to the position shown in 50 dotted lines in Fig. 3, then engaging the end of the arm beneath the rail head, with the lower end of the standard above the rail, and then swinging the upper portion of the structure across the rail to bring the lower end of the standard into engagement with the base flange, as shown in full lines. In this form 55 of the device I have shown the rail engaging part of the standard 14, which engages the base flange, as elongated in the direction of the length of the rail to hold the supporting

structure against tilting movement. Preferably this part consists of a transverse bar 60 secured between its ends to the body of the standard. It is not necessary that both rail engaging parts should be elongated and I have shown the rail engaging part of the arm as an integral part of the arm and of the same diameter as the body portion of the arm.

In Fig. 4 of the drawings I have shown 65 still another arrangement of the device in which the signal supporting standard 19 is in the form of a straight bar having at its lower end a transverse portion 20 to engage the rail base and having at a point spaced 70 from its lower end a slot 21. The arm 22 extends through the slot 21 and is pivotally mounted therein by means of a screw or pin 23. The lower end of the arm 22 is bent to form a hook 24 which engages over the rail 75 head on that side of the rail opposite the standard. The upper end of the arm 22 extends a short distance beyond the standard and can be engaged by the foot of the operator to manipulate the hook 24 in connecting the device with and disconnecting the same 80 from the rail. In this instance it will be observed that the offset or laterally extending portion of the device is provided by arranging the standard in an inclined position 85 rather than by bending the same.

While I have shown and described certain 90 embodiments of my invention I wish it to be understood that I do not desire to be limited to the details thereof as various modifications 95 may occur to a person skilled in the art.

Having now fully described my invention, 100 what I claim as new and desire to secure by Letters Patent, is:

1. In a railway track signal comprising 105 two members connected one to the other at a point spaced from the lower ends thereof and each having at its lower end a rail engaging part, said parts being so arranged that one of said parts will engage the base flange of the rail on one side of the rail and the other of said parts will engage the lower side of the rail head on the other side of the rail, one of said members having a laterally 110 extending part the weight of which will hold 115 said rail engaging parts in operative engagement with the respective parts of the rail, and a signal carried by one of said members.

2. In a railway track signal, a standard 120 having at its lower end a rail engaging part and having its upper portion offset laterally from the lower portion thereof, a signal carried by the upper portion of said standard, and an arm pivotally mounted on said standard at a point spaced from the lower end thereof and having at its lower end a rail engaging part, said rail engaging parts being so arranged that one of them will engage the lower side of the rail head on that side of the rail opposite said offset portion 125 130

of said standard, and the other part will engage the base flange of the rail on that side of the rail adjacent to said offset portion, and said parts will be held in supporting engagement with the rail by the weight of the offset portion of said standard.

3. In a railway track signal, a standard having at its lower end a rail engaging part and having its upper portion offset laterally from the lower portion thereof, a signal carried by the upper portion of said standard, and a second rail engaging part movable supported by said standard, said rail engaging parts being so arranged that one of said parts will engage the base flange of the rail on that side of the rail adjacent to the offset portion of said standard and the other of said parts will hook under the rail head on the other side of the rail.

20 4. In a railway track signal, a standard having at its lower end a rail engaging part and having its upper portion offset laterally from the lower portion thereof, a signal carried by the upper portion of said standard, and an arm pivotally mounted on said standard at a point spaced from the lower end thereof and having a rail engaging part, said rail engaging parts being so arranged that one of said parts will be supported by the base flange of the rail on that side of the rail adjacent to the offset portion of the standard and the other of said parts will hook under the rail head on the other side of said rail.

35 5. In a railway track signal, a standard having at its lower end a rail engaging part and having its upper portion offset laterally from the lower portion thereof, a signal carried by the upper portion of said standard, and an arm pivotally mounted on said standard at a point spaced from the lower end thereof and having a rail engaging part, said rail engaging parts being so arranged that one of said parts will be supported by the base flange of the rail on that side of the rail adjacent to the offset portion of the standard and the other of said parts will hook under the rail head on the other side of said rail, said arm having a part extending upwardly beyond its point of connection with said standard and serving as a handle for actuating said arm.

6. In a railway track signal, a standard having at its lower end a rail engaging part and having its upper portion offset laterally from the lower portion thereof, a signal carried by the upper portion of said standard, and an arm pivotally mounted on said standard at a point spaced from the lower end thereof and having a rail engaging part, said rail engaging parts being so arranged that one of said parts will be supported by the base flange of the rail on that side of the rail adjacent to the offset portion of the standard and the other of said parts will hook under the rail head on the other side of said

rail, and a spring connected with said standard and with said arm to hold said members in adjacent positions when said signal is not in use.

7. In a railway track signal, a standard, 70 an arm mounted on said standard at a point spaced from the lower end thereof, rail engaging bars secured to the lower ends of said standard and said arm and extending transversely thereto, said rail engaging bars being 75 so arranged that one of said bars will engage the base flange of the rail on one side of the rail and the other of said bars will engage the lower side of the rail head on the other side of the rail, said standard having a part extending laterally beyond that side of the rail which is engaged by the first mentioned bar, and the signal carried by said standard.

8. In a railway track signal, a standard having at its lower end a part to hook under 85 the head of a rail on one side thereof, an arm mounted on said standard at a point spaced from the lower end thereof and having a part to engage the base flange of the rail on that side thereof opposite the side engaged by said 90 part of said standard, said standard having a portion extending beyond the last mentioned side of said rail and serving by gravity to hold the first mentioned part of said standard and said part of said arm in engagement 95 with the respective parts of said rail, and a signal carried by said standard.

9. In a railway track signal, a standard having its lower end adapted to be supported 100 on the base flange of a rail on one side thereof, an arm mounted on said standard at a point spaced from the lower end thereof and having a part to hook under the rail head on the other side of said rail, said standard also having a part extending laterally from 105 that part of said rail on which said standard is supported and serving by gravity to hold said standard and said arm in supporting engagement with said rail, and a signal carried by said standard.

10. In a railway track signal, a supporting structure comprising two members rigidly connected one to the other at a point spaced from the lower ends thereof, said members being so arranged that the lower end of one 110 member will engage the base flange of a track rail and the lower end of the other member will hook over the head of the rail on that side of the rail opposite the first mentioned member, one of said members having a laterally extending part the weight of which serves to hold the lower ends of said members in engagement with said parts of the rail, and a signal carried by said supporting structure.

11. In a railway track signal, a standard having at its lower end a part to engage the base flange of a track rail and having its upper portion offset on that side of the rail which is engaged by the lower end thereof, a 130

signal carried by the offset portion of said standard, and an arm rigidly secured to said standard and having a part to engage the lower side of the rail head on that side of the rail opposite said standard.

12. In a railway track signal, a supporting structure, comprising two members connected one to the other at a point above the lower ends thereof and each having at its lower end a rail engaging part, said members being so arranged that one rail engaging part will engage the base flange of the rail on one side of the rail and the other rail engaging member will hook over the rail head on the other side of the rail, one of said rail engaging parts being elongated in the direction of the length of the rail to hold said structure against tilting movement, said structure having a part so arranged that the weight thereof will hold said rail engaging parts in operative engagement with said rail, and a signal carried by said supporting structure.

13. In a railway track signal, a standard having at its lower end a part to engage the base flange of a rail and having a slot extending through the same at a point spaced from said lower end, an arm extending through said slot and pivotally mounted therein and having at its lower end a hook shaped portion to engage over the head of the rail on that side thereof opposite said standard and to support said standard in an inclined position, and a signal carried by said standard.

14. In testimony whereof, I affix my signature hereto.

RONALD M. WILSON.
